SLICE RECEIVING TRAY

George R. Wood, Montreal, Quebec, Canada, assignor to Toledo Scale Company, Toledo, Ohio, a corporation of New Jersey

Application April 12, 1943, Serial No. 482,767

3 Claims. (Cl. 146—102)

This invention relates to food handling apparatus of the type in which a commodity to be sliced is reciprocated past the edge of a rotary circular knife blade and slices are severed from the commodity on each forward stroke, and more particularly to means for mounting a slice-receiving tray on such a device.

In slicing machines of the class described, after each slice of commodity has been severed by the knife, it is usually deflected by a so-called deflector plate onto a slice-receiving portion of the machine. In many such machines the slice receiver is constructed integrally with the base of the machine. This form of construction has several disadvantages, among them the additional weight of the machine which results from using a heavy enough slice-receiving section of the machine to serve as a portion of the frame, and the difficulty of cleaning a slice-receiving portion of the machine which is not removable. Slicing machines, because of the greasy nature of the meat and other commodities which are sliced thereon, are apt to accumulate grease and dirt in all cracks, nooks and crannies from which it periodically must be carefully removed. It is hardly sufficient merely to wipe the commodity contacting parts of the machine, since wiping does not of course remove all the grease, the remaining portion of which may become rancid and unsanitary.

It is an object of this invention to provide a slice-receiving tray, and means for mounting such a tray on a slicing machine which permits the tray to be quickly and easily removed from the machine.

It is another object of this invention to provide a slice-receiving tray which can be removed bodily from the slicing machine for immersion in boiling water or other cleansing and sanitizing liquid.

It is a further object of this invention to provide a slice-receiving tray for mounting on a slicing machine which conforms to the contour of the remaining portions of the machine and which permits the main frame of the machine to be cut away and thus reduced in weight.

More specific objects and advantages are apparent from the description, in which reference is had to the accompanying drawings illustrating a preferred form of device embodying the invention.

In the drawings:

Fig. I is a view in perspective, from the left front corner of a slicing machine, incorporating a slice-receiving tray embodying the invention.

Fig. II is a plan view of a slice-receiving tray embodying the invention, certain parts being broken away.

Fig. III is a fragmentary vertical sectional view,

taken substantially on the line III—III of Fig. II.

Fig. IV is an enlarged fragmentary sectional view, taken substantially on the line IV—IV of Fig. II.

Fig. V is an enlarged detailed sectional view, taken substantially on the line V—V of Fig. II.

Fig. VI is a view similar to Fig. I but of a different type of slicing machine embodying a modification of the invention.

Fig. VII is a plan view of a slice-receiving tray embodying a modification of the invention.

Fig. VIII is a fragmentary vertical sectional view, taken substantially on the line VIII—VIII of Fig. VII.

These specific drawings and the specific description that follows merely disclose and illustrate the invention and are not intended to impose limitations upon the claims.

20 A slicing machine of the type shown in Fig. I comprises a base 10 on which is erected a motor housing 11 and means for rotatably mounting a circular knife 12. A gauge plate 13 is mounted on the base 10 with its face in a plane parallel to the plane of the knife 12, and can be adjusted by means of a knob 14 in a direction perpendicular to the plane of its face. A commodity tray 15 is provided for carrying commodities past the edge of the knife 12 which, 25 according to the setting of the gauge plate 13, severs a slice of the desired thickness from the commodity during each stroke. Slices of commodity so severed by the knife 12 are deflected by a deflector plate 16, located behind the knife 30 12, onto a slice-receiving tray 17 which is located below the deflector plate 16.

The slice-receiving tray 17 consists of a single-casting, preferably made of a light material such as aluminum. The slice-receiving tray has a 35 turned-over formed side 18 and a similar front 19, which continue the vertical planes of the left side and front of the base 10, the joining edges of the slice-receiving tray and base 10 being flush and having a continuous contour. The slice- 40 receiving tray 17 has a rear edge 20 which blends into the lower edge of the deflector plate 16 mounted above it, these adjoining edges having a continuous sweeping contour to prevent the accumulation of grease and dirt in the crack between the plate and the tray. A right edge 21 of the slice-receiving tray 17 sweeps up and over the edge of a rectilinear section of the base 10, and has an overhanging lip 22 which covers the crack between the adjacent portions of the base 45 10 and the slice-receiving tray 17, to prevent the entrance of grease and particles of commodity into such crack. Two holes 23 are drilled horizontally through the swept-up right side 21 of the slice-receiving tray to accommodate a pair of 50 rods 24 on which the gauge plate 13 is mounted.

The base 10 has two inverted U shaped channel sections 25 and 26 located beneath the slice-receiving tray 17, which form a right triangle and cut diagonally from the right front to left rear corner of the slice-receiving tray. These channel members must, of course, be constructed of substantial and heavy material in order to form part of the main structure of the slicing machine, and since they are cut angularly across the space occupied by the slice-receiving tray instead of extending along the two outside edges of the slice-receiving tray, their weight is substantially reduced.

The slice-receiving tray is removably mounted on the base 10 by two pins 27, each of which is riveted in a downwardly extending ear 28 of a substantially C shaped clamp 29 bolted to the frame members 25 and 26, near the rear of the right triangle formed thereby. The pins 27 engage in two countersunk holes 30 drilled horizontally through a pair of tabs 31, which are cast integrally with the slice-receiving tray 17 and extend downwardly from the undersurface of the tray. The slice-receiving tray is held in place by the engagement of the head of a bolt 32, which extends vertically through the frame 10 near the point of junction of the two members 25 and 26 in the forward part of the frame, with a counterbore 33 in a boss 34 formed on the underside of the slice-receiving tray 17. The bolt 32 passes through an oversize hole 35 in the frame member 25 and through two washers 36, located one above and one below such hole, and thus its position can be varied to cause it properly to engage the counterbore 33. When the bolt 32 is in the proper position, a nut 37, threaded on the bolt, can be tightened to compress the washers 36 and hold the bolt in place.

In the embodiment of the invention shown, since the gauge plate 13 is mounted upon rods 24 which extend through the holes 23 in the slice-receiving tray, the gauge plate 13 must be removed before the slice-receiving tray can be removed. Assuming either that the gauge plate has been so removed, or that a gauge plate of a different type which does not interfere with the removal of the slice-receiving tray is employed in the slicing machine, the tray is removed by lifting its forward edge, thus disengaging the head of the bolt 32 from the counterbore 33, and then pulling the slice-receiving tray forward to slide the tabs 31 off the pins 27. A reversal of these operations is employed to replace the slice-receiving tray.

The embodiment of the invention illustrated in Figs. VII and VIII is shown in Fig. VI as employed in a slicing machine of the gravity feed type, which comprises a base 10a, motor housing 11a, circular knife 12a, which in this case is inclined to the vertical, gauge plate 13a, similarly inclined, gauge plate adjusting knob 14a and inclined commodity tray 15a. Commodities placed on the tray 15a slide downwardly thereon by gravity and, as the tray 15a is reciprocated past the edge of the knife 12a, slices severed from the commodity are deflected by a deflector plate 16a onto a slice-receiving tray 17a.

The slice-receiving tray 17a is constructed substantially identically with the slice-receiving tray illustrated in Fig. I with the exception that, since the gauge plate 13a is mounted on the base 10a in a different manner, no provision need be made for the passage of supporting rods through a section of the slice-receiving tray.

The slice-receiving tray 17a is removably mounted on the base 10 by means of a pair of formed spring clips 38a, which are welded to the undersurface of the tray 17a and which engage with an inverted U shaped frame member 26a forming a part of the base 10a. The clips 38a pass through two apertures 39a which are formed in the left side of the channel member 26a. The slice-receiving tray 17a is held down on the channel member 26a and upon a second channel member 25a by a pair of cone-shaped knurled nuts 40a, which are threaded on two studs 41a extending horizontally from the side of the channel member 25a, in which they are secured by two vertical set screws 42a. The studs 41a extend through oversize holes in a pair of angle brackets 43a welded to the undersurface of the slice-receiving tray 17a, the cone-shaped ends of the nuts 40a being engaged in the holes in the brackets 43a.

To remove the slice-receiving tray 17a, the knurled nuts 40a are unscrewed from the threaded studs 41a, and the slice-receiving tray is moved bodily to the left (Figs. VII and VIII) to disengage the brackets 43a from the ends of the studs, and to disengage the clips 38a from beneath the channel member 26a.

A slice-receiving tray embodying the invention thus can be removed for thorough cleansing, and can be replaced quickly and simply on the machine for further use.

The embodiments of the invention that have been disclosed may be modified to meet various requirements.

Having described the invention, I claim:

1. In a slicing machine, in combination, a base, a slice receiver mounted on said base and externally blending into the contour of said base, that portion of said base extending beneath said slice receiver being cut away and skeletonized to reduce weight, said slice receiver being readily removable from said base, and means for mounting said slice receiver comprising a pair of apertured members mounted on the undersurface of said slice receiver and engageable with horizontal studs mounted in a member adjustably attached to a portion of said base extending beneath said slice receiver.

2. In a slicing machine, in combination, a base, a slice receiver mounted on said base and externally blending into the contour of said base, and means for mounting said slice receiver comprising a member adjustably attached to said base and including a plurality of horizontal pins, apertured lugs depending from said slice receiver and engageable with said pins, and a vertical pin mounted for horizontal adjustment and engageable in a recess of a boss depending from said slice receiver to maintain the engagement of said apertured lugs on said horizontal pins.

3. In a device of the class described, in combination, a base, a slice receiver mounted on said base and externally blending into the contour of said base, said slice receiver being readily removable from said base, and means for securing said slice receiver in place on said base, said means comprising spring clips attached to the under side of the slice receiver and adapted to grip a rib of the base between the slice receiver and the clips, and other members depending from said slice receiver adapted to engage and be secured by clamping means threaded onto studs projecting horizontally from another rib of said base.

GEORGE R. WOOD.
